(57) **CLAIM**

The ornamental design for a storage container seal, as shown and described.

DESCRIPTION

FIG. 1 is a top, front and left side isometric view of a first embodiment of a storage container seal showing my new design;

FIG. 2 is a bottom, rear and left side isometric view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof;

FIG. 8 is a right side elevation view thereof;

FIG. 9 is a cross-sectional view taken along line 9-9 of FIG. 3;

FIG. 10 is a cross-sectional view taken along line 10-10 of FIG. 3;

FIG. 11 is a top, front and left side isometric view of a second embodiment of a storage container seal showing my new design;

FIG. 12 is a bottom, rear and left side isometric view thereof;

FIG. 13 is a top plan view thereof;

FIG. 14 is a bottom plan view thereof;

FIG. 15 is a front elevation view thereof;

FIG. 16 is a rear elevation view thereof;

FIG. 17 is a left side elevation view thereof;

FIG. 18 is a right side elevation view thereof;

FIG. 19 is a cross-sectional view taken along line 19-19 of FIG. 13;

FIG. 20 is a cross-sectional view taken along line 20-20 of FIG. 13;

FIG. 21 is a top, front and left side isometric view of a third embodiment of a storage container seal showing my new design;

FIG. 22 is a bottom, rear and left side isometric view thereof;

FIG. 23 is a top plan view thereof;

FIG. 24 is a bottom plan view thereof;

(Continued)

FIG. 25 is a front elevation view thereof;
 FIG. 26 is a rear elevation view thereof;
 FIG. 27 is a left side elevation view thereof;
 FIG. 28 is a right side elevation view thereof;
 FIG. 29 is a cross-sectional view taken along line 29-29 of FIG. 23;
 FIG. 30 is a cross-sectional view taken along line 30-30 of FIG. 23;
 FIG. 31 is a top, front and left side isometric view of a fourth embodiment of a storage container seal showing my new design;
 FIG. 32 is a bottom, rear and left side isometric view thereof;
 FIG. 33 is a top plan view thereof;
 FIG. 34 is a bottom plan view thereof;
 FIG. 35 is a front elevation view thereof;
 FIG. 36 is a rear elevation view thereof;
 FIG. 37 is a left side elevation view thereof;
 FIG. 38 is a right side elevation view thereof;
 FIG. 39 is a cross-sectional view taken along line 39-39 of FIG. 33; and,
 FIG. 40 is a cross-sectional view taken along line 40-40 of FIG. 33.
